UNITED STATES PATENT OFFICE.

ROBERT CHARLES, OF ST. LOUIS, MISSOURI, ASSIGNOR OF ONE-HALF TO
ROBERT S. CHARLES, OF SAME PLACE.

GRATE.

SPECIFICATION forming part of Letters Patent No. 247,746, dated October 4, 1881.

Application filed August 1, 1881. (No model.)

To all whom it may concern:

Be it known that I, ROBERT CHARLES, of St. Louis, Missouri, have made a new and useful Improvement in Grates, of which the following is a full, clear, and exact description, reference being had to the annexed drawings, making part of this specification, in which—

Figure 1 is a view in perspective, showing the front part of a stove having the improvement in question, to exhibit which the front wall and grate-bars are broken away; and Fig. 2, a vertical transverse section of the same.

Similar letters denote similar parts.

The aim of the present invention is to provide an improved means for concentrating and maintaining a comparatively small body of fire at a high level in a grate or fire-place, and so that the top of the fire may come near the top of the fire-place.

In the drawings, A represents a stove (only that portion thereof immediately connected with the improvement being shown) having the top plate, B, the fire-place C, and the grate D, the latter having the bars d^1 d^2 and end walls, d^3 d^4 , substantially as in the ordinary stove.

E represents a plate made to fit the grate transversely, having its edges e e' tapered to fit the taper of the back d^3 and front d^4 of the grate, and extending from the bottom d^5 of the fire-pot well up toward the top of the fire-place. The plate is intended to form a false end wall of the grate, being removable there-

from and adjustable endwise therein, and so that it can be placed and held at any desired point between the ends of the grate, and for 35 the time being forming one of the ends of the fire-place.

To hold it in position the plate is provided with a brace, F, the upper end, f , of which is fastened to the plate and the lower end bent 40 to form a shoulder, f' , which bears against the side of one of the grate-bars d ; and to better keep the brace in place it is also shaped at f^2 to bear down upon the top of the grate-bars, substantially as shown. The end or foot of 45 the brace is thus kept from slipping horizontally and from dropping through the grate-bottom. At the same time the plate F can be removed from the fire-place by simply lifting it from off the grate. In this way the fire-place 50 can be shortened in width as desired, and by confining the fire between the plate F and the end wall but a small body of fire is needed, even to bring the top of the fire near the top of the fire-place, and so as to be near the utensils 55 upon the stove.

The plate F may be a grating.

I claim—

The combination of the plate E, brace F, and grate D, substantially as described.

ROBERT CHARLES.
